UNITED STATES PATENT OFFICE.

JACOB WUEST, OF ANGLUM, MISSOURI.

DESIGN FOR A PROTECTOR FOR LAMP-CHIMNEYS.

SPECIFICATION forming part of Design No. 29,289, dated August 30, 1898.

Application filed July 27, 1898. Serial No. 687,023. Term of patent 7 years.

To all whom it may concern:

Be it known that I, JACOB WUEST, a citizen of the United States, residing at Anglum, in the county of St. Louis and State of Missouri, have invented and produced a new and original Design for Protectors for Lamp Chimneys or Globes; and I do hereby declare the following to be a full, clear, and exact description of the same, reference being had to the accompanying drawings, forming a part thereof.

This invention relates to a novel design for protectors for lamp chimneys and globes for the purpose of excluding flies, bugs, and other insects from the chimney or globe; and it consists in novel features which will be hereinafter fully explained.

The annexed drawings, to which reference is made, fully illustrate my invention, in which—

Figure 1 represents a side view of my device. Fig. 2 is a plan view of the same; and Fig. 3 is a vertical sectional view, these three

views being deemed necessary to illustrate my design.

The leading feature of my design consists in the wire-gauze having the depressions below the apex and the bottom of the gauze surrounded by a band presenting a circle.

In my design it will be seen that arms extend from the circle, and these arms constitute one of the essential features of my design.

A designates the body of the protector for lamp chimneys and globes, and B is the circular band to which this body is secured, as well as the arms C.

What I claim is—

The design for protector for lamp chimneys and globes, herein shown and described.

In testimony whereof I affix my signature in presence of two witnesses.

JACOB WUEST.

Witnesses:

GEORGE SIGLINGER,
ERNST MARGRAF.
